UNITED STATES PATENT OFFICE

123,182

DESIGN FOR A HAT

Samuel Stricker, New York, N. Y.

Application August 31, 1940, Serial No. 94,754

Term of patent 3½ years

To all whom it may concern:

Be it known that I, Samuel Stricker, a citizen of the United States of America, residing in New York city, county of New York, and State of New York, have invented a new, original, and ornamental Design for a Hat, of which the following is a specification, reference being had to the accompanying drawing, forming part thereof, wherein:

The characteristic feature of my design resides in the ornamental arrangement of lines on the hat, as shown.

I claim:

The ornamental design for a hat, substantially as shown, and described.

SAMUEL STRICKER.
